DESIGN FOR A CONFECTION WAGON

Arthur Handy Henry, Philadelphia, Pa.

Application September 6, 1934, Serial No. 53,208

Term of patent 14 years

To all whom it may concern:

Be it known that I, Arthur H. Henry, a citizen of the United States, residing at Philadelphia, in the county of Philadelphia and State of Pennsylvania, have invented a new, original, and ornamental Design for a Confection Wagon, of which the following is a specification, reference being had to the accompanying drawing, forming part thereof.

I claim:—

The ornamental design for a confection wagon, as shown.

ARTHUR HANDY HENRY.
